(57) **CLAIM**

I claim the ornamental design for a percussive massage device, as shown and described.

DESCRIPTION

FIG. 1 is a top perspective view of a percussive massage device.

FIG. 2 is a top view of the percussive massage device depicted in FIG. 1.

FIG. 3 is a bottom view of the percussive massage device depicted in FIG. 1.

FIG. 4 is a front view of the percussive massage device depicted in FIG. 1.

FIG. 5 is a rear view of the percussive massage device depicted in FIG. 1.

FIG. 6 is a left side view of the percussive massage device depicted in FIG. 1.

FIG. 7 is a right view of the percussive massage device depicted in FIG. 1; and,

FIG. 8 is a top perspective view of the percussive massage device depicted in FIG. 1 including environmental subject matter that forms no part of the claimed design.

The broken lines depict portions of the percussive massage device that form no part of the claimed design. The broken lines in FIG. 8 depict environmental subject matter and form no part of the claimed design.

1 Claim, 8 Drawing Sheets
